UNITED STATES PATENT OFFICE.

MEYER L. ROBBINS, OF NEW YORK, N. Y.

METHOD OF MAKING CUFF-BUTTONS.

1,155,837.

Specification of Letters Patent.

Patented Oct. 5, 1915.

Application filed February 19, 1915. Serial No. 9,265.

To all whom it may concern:

Be it known that I, MEYER L. ROBBINS, a citizen of the United States, and a resident of New York city, borough of Manhattan, in the county of New York and State of New York, have invented certain new and useful Improvements in Methods of Making Cuff-Buttons, of which the following is a specification.

- 10 This invention relates to certain new and useful improvements in making cuff buttons and particularly to making cuff buttons of a kind commonly known and referred to as link buttons.
- 15 The object of my invention is to produce by a new and improved method a link button composed of a single continuous integral piece of metal and further to make such integral buttons from a blank strip of solid metal having a web and an accumulation of metal of greater thickness than the web along each longitudinal edge, by which new and improved method such buttons of perfect shape, form and construction can be 25 made entirely by machinery very rapidly and economically without seam or soldered joint.

In the accompanying drawings I have illustrated one way of carrying out my new and improved method and in these drawings Figure 1 is a perspective view of the flanged or substantially I beam shaped blank strip from which the individual buttons are to be made. Fig. 2 shows the same blank somewhat changed in dimensions of its various component parts. Fig. 3 is a perspective view of one of the individual blanks cut from the blank strip. Fig. 4 is a similar view of the same with the accumulations of metal at the two ends compressed and brought into a more or less bulbous shape adapted for forming certain parts of the button. Fig. 5 is a side elevation of the individual blank after it has been subjected to dies for shaping it and whereby a central longitudinal plane fin is formed around the individual blank. Fig. 6 is an edge view of this blank and fin. Fig. 7 is an elevation of the individual blank after the fin has been cut off. Fig. 8 is an edge view of the same. Fig. 9 is a perspective view of the individual blank after the bottom bulb has been pressed into disk shape and the surplus metal appears as a fin around the base or disk. Fig. 10 is a similar view of the same after the fin surrounding the base has been

cut off by suitable tools. Fig. 11 is a side view of the button after the stem has been bent laterally at its upper part so as to bring it in the form of a finished button. Fig. 12 is a similar view showing a modification in which the disk or base has been pressed to be cupped or rounded convexly on its under surface.

In the drawings 15 represents a blank strip from which the buttons are to be formed, said strip preferably consisting of precious metal, such as gold or silver and this blank strip 15 has a cross section composed of a web 19 and an accumulation of metal along each edge of the web as shown at 17 and 18 so that this blank strip has substantially the shape in cross section of an I-beam. This blank strip is rolled between suitable rolls or drawn between suitable dies 70 so as to reduce the thickness of the web 19 and widen the lower flanges or accumulation of metal 18 and also slightly reduce in width the upper accumulation of metal represented by 17. This blank is then cut transversely 80 to its length by a suitable tool, into a series of individual blanks, one for each button as shown in Fig. 3, each individual blank consisting of a stem 22 which has been formed out of the web 19 of the original blank strip 15 and this stem 22 has an accumulation 20 of metal at its upper end and an accumulation 21 of metal at its lower end, the upper accumulation or head 20 being formed or cut out of the top flange 17 of the blank 93 strip 15 and the lower accumulation of metal or base 21 being cut or formed out of the bottom flange 18 of the original blank strip 15. This individual blank is then subjected to pressure between suitable dies so as to 85 compress the head 20 into approximately a ball or bean shape as shown at 23 in Fig. 4 and the base 21 into a ball or bulb shape as shown at 24 in Fig. 4. The individual blank thus obtained and illustrated in Fig. 4 is 100 then placed into a press and by means of suitable dies in said press this blank is compressed to form the two opposite sides of the stem 22, substantially semi-circular as shown at 27 in Figs. 5 and 6 and to round the contours of the head 23 so as to bring it into a so called bean shape as shown at 25 in Figs. 5 and 6. At the same time the base 24 of Fig. 4 is converted into an approximately oval or elliptical base portion 28 rounded at 110 the top, bottom and side surfaces. By pressing the metal between dies as aforesaid the

2
surplus metal is forced out laterally between the dies and surrounds the individual blank as a fin 26 in the longitudinal central plane of the individual blank, as far as completed 5 and as shown in Figs. 5 and 6. This blank is then subjected to the action of a properly shaped cutting die which cuts off this fin along its inner edges leaving the inner blank in the shape shown in Fig. 7, which shows 10 the same in side view and Fig. 8 shows it in edge view. Then the individual blank is subjected to another die which compresses and flattens out more or less the base 30 of Figs. 7 and 8, which base is formed out of 15 the base portion 24 of Fig. 4 and thereby this base portion is converted into a flat circular disk 31 and by this action upon the base of the individual blank, the base 30 of Figs. 7 and 8 is converted into the disk 31 20 and the surplus metal is forced beyond the edges of this disk to surround the disk as a fin 32, Fig. 9. By another suitable cutting die the fin is cut from the base disk 31 along the inner edges of said fin and thereby the 25 finished button with the straight stem 27 and a bean or head 25 at the upper end of the stem and a flat disk 31 at the lower end of the stem is formed.

In such cuff or link buttons of the preferred style the upper half of the stem is 30 bent laterally as shown in Fig. 11. In some cases it is desired that the base be rounded on its outer surface convexly and for this purpose the flat base 31 of Fig. 10 is subjected to a pressing action between suitable 35 dies so as to cup it as shown at 35 in Fig. 12. The button thus obtained is a solid button with a stem, a base and a head or bean all composed of a single continuous integral 40 piece of metal without seam or joint. The button is then polished and finished in the usual way.

Having described my invention what I claim as new and desire to secure by Letters

45 Patent is:—

1. The herein described method of making one piece buttons having a solid stem, head or bean and a base without seam or joint, consisting in cutting a metal blank 50 strip having a web and an accumulation of metal of greater thickness than the web, along each longitudinal edge of said web, into a series of individual blanks by cuts

which extend transversely of the length of the blank strip through the web and top and bottom accumulations of metal, then shaping the accumulations of metal at each end of the individual button blank into substantially bulbous shapes and then flattening one of these bulbous shapes into a disk, substantially as set forth. 55

2. The herein described method of making one piece buttons having a solid stem, head or bean and a base without seam or joint, consisting in cutting a metal blank 60 strip having a web and an accumulation of metal of greater thickness than the web, along each longitudinal edge of said web, into a series of individual blanks by cuts which extend transversely of the length of the blank strip through the web and top and bottom accumulations of metal, then shaping the accumulations of metal at each end of the individual button blank into substantially bulbous shapes, removing the metal 65 surrounding the blank in the form of a fin and then pressing the bottom accumulation of metal into a disk, substantially as set forth. 70

3. The herein described method of making one piece buttons having a solid stem, head or bean and a base without seam or joint, consisting in cutting a metal blank 75 strip having a web and an accumulation of metal of greater thickness than the web, along each longitudinal edge of said web, into a series of individual blanks by cuts which extend transversely of the length of the blank strip through the web and top and bottom accumulations of metal, then shaping the accumulations of metal at each end of the individual button blank into substantially bulbous shapes, removing the metal 80 surrounding the blank in the form of a fin and then pressing the bottom accumulation of metal into a disk and finally removing the fin surrounding said disk, substantially 85 as set forth. 90

Signed at New York city, borough of Manhattan in the county of New York and 100 State of New York this 25 day of November A. D. 1914.
